UNITED STATES PATENT OFFICE.

EDWARD WELLS, OF NEW HAVEN, CONNECTICUT.

IMPROVEMENT IN LANDAULET-CARRIAGE FRONTS.

Specification forming part of Letters Patent No. 133,910, dated December 10, 1872.

To all whom it may concern:

Be it known that I, EDWARD WELLS, of New Haven, in the county of New Haven and State of Connecticut, have invented a new Improvement in Landaulet Carriage; and do hereby declare the following, when taken in connection with the accompanying drawing and the letters of reference marked thereon, to be a full, clear, and exact description of the same, and which said drawing constitutes part of this specification, and represents, in—

Figure 1, a side view; in Fig. 2, a transverse section, showing the sash closed; in Fig. 3, the same, showing the manner of opening the sash; and in Fig. 4, the sash detached.

This invention relates to an improvement in that class of carriages known as "landaulets;" the object being the construction of the front so that the sides may be readily opened; and it consists in the arrangement of the sash upon opposite sides in channels, so that the forward edge of either may be turned into a channel in the front, and the two side sashes turned into their respective channels in the front, as more fully hereinafter described.

A represents the sill; B, the door-post; C, the top; D, the front post of a landaulet front, constructed so as to be placed upon or taken from the front in the usual manner. The front or space between the two posts D D is filled by a sash, E; the sides, respectively, by a sash, F H. On the sill A at the sides a channel, a, is formed, and on the front sill two channels, b d, are formed, both communicating with the side channels. The sash is constructed with

a stud or pivot, f, at the bottom, as seen in Fig. 4; these studs, setting into the channel, support the sash, a similar arrangement being made at the top.

When closed the sash stands in the position seen in Fig. 2.

To open the side sash, draw in the forward edge, the stud upon that edge passing into one of the channels in front, as seen in Fig. 3, the stud upon the front edge following in the channel upon the side, until the sashes are drawn around into their respective channels, one behind the other, as seen in Fig. 3, or into proper position, which opens both sides of that part of the carriage; and the sashes may be closed by simply drawing the sash back to its first position, it being readily guided into such position by the channels. Thus either or both channels may be opened or closed at pleasure, and may be prevented from rattling by any of the known devices for that purpose.

I have represented and prefer channels for the sash to work in; but a track may be arranged corresponding to the said channels to answer for the same purpose.

I claim as my invention—

In a landaulet-carriage front, the arrangement of the side sashes F H in channels or tracks, substantially as described, so that each sash may be turned from the side to the front and back, substantially as set forth.

EDWARD WELLS.
